UNITED STATES PATENT OFFICE

PAUL MOUTON, OF PARIS, FRANCE, ASSIGNOR TO ORIENTAL SILK PRINTING COMPANY, OF NEW YORK, N. Y., A CORPORATION OF NEW JERSEY

DESIGN FOR A TEXTILE FABRIC OR SIMILAR ARTICLE

Application filed December 12, 1930. Serial No. 37,959. Term of patent 14 years.

To all whom it may concern:

Be it known that I, PAUL MOUTON, a citizen of the Republic of France, and resident of the city of Paris, France, have invented a new, original, and ornamental Design for a Textile Fabric or Similar Article, of which the following is a specification, reference being had to the accompanying drawing, forming part thereof.

The drawing shows one repeat unit of the design and by matching the horizontal edges and the vertical edges of the illustration a continuation of the design will result.

The figure is a plan view of a textile fabric illustrating my new and ornamental design.

I claim:

The ornamental design for a textile fabric or similar article as shown and described.

PAUL MOUTON.
